[57] CLAIM

The ornamental design for a keyboard stand, as shown and described.

DESCRIPTION

FIG. 1 is a perspective view of a keyboard stand showing my new design, the broken line showing of a keyboard is for illustrative purposes only;

FIG. 2 is a top plan view thereof;

FIG. 3 is a bottom plan view thereof;

FIG. 4 is a right end elevational view the left end being a mirror image thereof;

FIG. 5 is a front elevational view thereof;

FIG. 6 is a rear elevational view thereof;

FIG. 7 is a perspective view of an alternate embodiment of the keyboard stand shown in FIG. 1; and

FIG. 8 is a top plan view of FIG. 7.

The second embodiment of FIG. 7 is identical to the first embodiment of FIGS. 1 through 6 except that it is shorter in length.

Fig. 1Fig. 2Fig. 3Fig. 4Fig. 5Fig. 6Fig. 8Fig. 7
